UNITED STATES PATENT OFFICE.

ALBERT E. JAMES, OF NATCHEZ, MISSISSIPPI.

OIL-BURNING STOVE.

Application filed October 22, 1926. Serial No. 143,478.

My invention relates to improvement in the construction and arrangement of the pipes that conduct oil from the fuel-tank to the burners of oil-burning stoves, and to an extension of one of the pipe members to meet another useful need, and the objects of my improvement are, first, to provide a chamber for sediment and water that otherwise may accumulate in the feed-pipe and burners; second, to provide a chamber housing a stove-leveling float-actuated indicator; third, to provide means for convenient removal and reassembling of the main oil-conveying pipes as a unit; fourth, to facilitate removal of accumulations in the sediment chamber.

I attain these objects by the means illustrated in the accompanying drawings, in which I have shown two types of oil-burning stoves incorporating my improvement. My invention is not, however, limited to the types shown for purposes of illustration, but may assume other forms.

Figure 1 is a front view of a type of stove that must be accurately leveled that each of the burners may be accurately regulated in accord with the marked dials 15, 15^a, 15^b, by means of the movable indicator handles 16, 16^a, 16^b, the height of flame being controlled by elevating or lowering the individual burners.

Figure 2 is a vertical sectional view of an upper portion of member 9, Fig. 1, showing the members housed therein.

Figure 3 illustrates another type of stove in which the burners are stationary, being detachably mounted directly upon the feed-pipe 8.

The designating numerals in Figures 1 and 3 are disposed in orderly progression to facilitate descriptive reference, similar numerals in Figure 2 indicating corresponding parts.

In my improved construction I have taken advantage of the fact that when two or more receptacles containing oil and a heavier than oil fluid, such as water, are properly connected by tubes or pipes, the heavier fluid will accumulate in the lowest receptacle, and I have so arranged the receptacles that the lower one 5, Figures 1 and 3, is disposed between the fuel-tank 1 and the smaller pipe 8 to which the burners 13, 13^a, 13^b are connected, which house the wicks (not shown) which are so injured when water enters the burners that it is necessary to replace them

with dry wicks before the stove can be operated successfully again.

Attached to and in communication with members 5 and 8 is a stand-pipe 9 which extends vertically, as shown in Fig. 1, to a point just below the stove-top. The height of this stand-pipe is important, as it should extend some distance above the normal oil-level to prevent overflow of oil at its top when the tank end of the stove is raised, as a careless servant may sometime do, in moving the stove when cleaning the kitchen floor.

Housed within 9 at its upper end is a float 10 and indicator 12, a cap 11 being used to close the top of 9 and to act as a guide for the wire used to connect the float and indicator, as shown. Member 4 is a threaded pipe union attaching member 3 to member 5, and when disconnected and the burners are detached from member 8, allows of removal from the stove of members 5, 8 and 9 as an assembled unit, greatly facilitating the cleaning of these members, and insures correct positioning of the burners when reassembled, which might not be the case were member 8 detached and taken out separately. Numeral 6, Figs. 1 and 3, indicates a drip-pan placed below the burners and fuel-distributing pipe to catch the oil in case leaks occur, and 7 indicates a removable pipe plug to facilitate cleaning out the sediment chamber 5.

In operation, my invention greatly facilitates the necessary leveling of the stove, that oil may be supplied at equal height in each of the burners 13, 13^a, 13^b. This is accomplished after the filled fuel-tank 1 is placed in position on the sub-tank 2 and oil has reached its level, shown by air bubbles ceasing to agitate the oil in 1. Then by raising either the right or left end of the stove as required until the indicator 12 just clears the cap 11, this heretofore troublesome task is easily accomplished. Screws arranged in the lower end of the stove-legs may be used for adjusting the height.

I preferably employ as a sediment chamber the pipe 5 of approximately three times the fluid capacity of the feed-pipe 8 in general use. It is evident, however, that a sediment chamber of other form, materials and construction may be positioned at any point between the fuel-tank and the burners that will admit of proper attachment. I, therefore, do not wish to be limited to the form

shown, but wish to include within the scope of this application all those forms of my invention that are in harmony with its spirit. Figure 3 shows a stove equipped 5 with my sediment chamber, but without the stand-pipe 9 and float-actuated stove-leveling indicator, as certain types of stoves do not require very accurate leveling.

What I claim as new and desire to secure 10 by Letters Patent is:

1. The combination in an oil-burning stove, of a closed end horizontally disposed fuel distributing pipe, having a downturned end, one or more burners in detachable communication with said distributing pipe, a sediment chamber of tubular form horizontally disposed below said fuel pipe and secured to and in free communication with said downturned end, a detachable conduit 15 connecting one end of said sediment chamber

ber with a source of fuel supply, and a removable threaded plug closing the free end of said sediment chamber, substantially as shown and described.

2. In an oil-burning stove, a removable unit composed of a horizontally disposed fuel distributing pipe having a closed free end and having its opposite end downturned, a sediment chamber of tubular form horizontally disposed below said fuel pipe 25 and secured to and in free communication with said downturned end, a removable threaded plug closing the free end of said chamber and a member of a pipe union attached to the opposite end of said chamber, 30 substantially as shown and described.

In witness whereof I have hereunto subscribed my name.

ALBERT E. JAMES.
